US00D990433S

(12) **United States Design Patent** (10) **Patent No.:** **US D990,433 S**
Kim et al. (45) **Date of Patent:** **** Jun. 27, 2023**

(54) **ADAPTER FOR SIGNAL TRANSMISSION**

(71) Applicant: **SENSORVIEW CO., LTD.**, Gyeonggi-do (KR)

(72) Inventors: **Byoung Nam Kim**, Gyeonggi-do (KR); **Hong Il Yoo**, Seoul (KR); **Gi Hun Kang**, Gyeonggi-do (KR)

(73) Assignee: **SENSORVIEW CO., LTD.**, Gyeonggi-do (KR)

(**) Term: **15 Years**

(21) Appl. No.: **29/710,298**

(22) Filed: **Oct. 22, 2019**

(30) **Foreign Application Priority Data**

Apr. 30, 2019 (KR) 30-2019-0020549

(51) **LOC (14) Cl.** **13-03**

(52) **U.S. Cl.** **D13/151**
USPC .....

(58) **Field of Classification Search**

USPC D13/151, 154, 133

CPC H01R 13/622

(57) **CLAIM**

The ornamental design for the Adapter for Signal Transmission, as shown and described.

DESCRIPTION

FIG. 1 is a perspective view of the Adapter for Signal Transmission, which is viewed from the front of the present design, showing my new design;

FIG. 2 is a perspective view of the Adapter for Signal Transmission, which is viewed from the back of the present design;

FIG. 3 is a front view of the Adapter for Signal Transmission;

FIG. 4 is a back view of the Adapter for Signal Transmission;

FIG. 5 is a left view of the Adapter for Signal Transmission;

FIG. 6 is a right view of the Adapter for Signal Transmission;

FIG. 7 is a top view of the Adapter for Signal Transmission; and

FIG. 8 is a bottom view of the Adapter for Signal Transmission.
